UNITED STATES PATENT OFFICE.

FREDERICK WEBSTER KIDDIE, OF LEAMINGTON, ENGLAND, ASSIGNOR TO WINGET
LIMITED, OF LONDON, ENGLAND.

PRESS FOR MOLDING CONCRETE BLOCKS AND THE LIKE.

1,371,174.

Specification of Letters Patent.

Patented Mar. 8, 1921.

Application filed June 15, 1920. Serial No. 389,230.

To all whom it may concern:

Be it known that I, FREDERICK WEBSTER KIDDIE, a subject of the King of Great Britain and Ireland, residing at 26 Binswood avenue, Leamington, in the county of Warwick, England, have invented new and useful Improvements in Presses for Molding Concrete Blocks and the like, of which the following is a specification.

10 The object of the present invention is to provide a machine which is specially adapted to the rapid production of evenly pressed and molded blocks, either by light hand labor or by other power, and more particularly for the production of concrete blocks for building purposes.

The machine is of the type in which a prepared plastic, or semi-plastic, mass of prepared material is placed in an open mold 20 and inserted under a plate or plunger which is caused to descend into the mold and to rise therefrom, after which the mold is withdrawn from that position and the pressed mass removed.

25 According to my improvements, the mold box is mounted on the ends of rocking arms operated by means of a lever and is lifted thereby in and out of its position for pressing in a suitable frame, thus eliminating 30 risk of damage to the inclosed mass from shocks during the change of position and obviating the use of springs, rollers and other devices which are liable to become clogged.

35 When in position for pressing, this box rests upon adjustable conical steel points fixed in the bed-plate, and corresponding sockets may be provided under the box so as to insure its exact position under the press after 40 each operation.

This box is provided with hinged sides or doors which are locked by catches.

A ram-plate or plunger is arranged to fit into the open top of the mold box and is 45 controlled by strong vertical rods affixed to the plate passing through suitable guide holes in the frame.

To these vertical guide rods, or to the central one only, is affixed a horizontal slide 50 inclosing a rectangular sliding block having a central horizontal hole transverse to the slide, through which is passed a strong rotatable pin. This pin projects and is held eccentrically in a driving wheel or disk

by which it is carried around in a circular 55 path, carrying with it the slide-block which adapts itself within the slide and conveys thereto a direct vertical pressure at all times of the stroke, which direct pressure is communicated to the ram-plate and the material 60 within the box, thus insuring a perfect evenness of the resulting block and avoiding the risk of its becoming tapered in shape through uneven filling.

The driving wheel or disk may have hand 65 grips to facilitate operation and may be connected with reducing gear to gain power.

The hand-wheel is detachable and any suitable power may be applied as an alternative.

If ornamental face blocks or slabs are desired, suitable plates may be inserted over 70 the top of the mold.

If bricks or small blocks are required, several mold boxes and plates can be used 75 at each operation. I find it convenient, however, when half blocks are to be molded to proceed as follows: The front wall of the mold box is slotted vertically with a closed thin slot, and this is occupied by a sliding 80 plate or slide which fits it loosely. This slide can be pushed in so as to extend across the box to the opposite wall, and is long enough to leave a piece projecting at the front, where it may have a hole or be otherwise adapted to serve as a handle.

The ram may have a thin strip fixed transversely upon its under surface, corresponding exactly with the position of the slide.

The strip and the slide are central in the 90 length of the mold box for forming two half blocks at one and the same time. The strip may be held to the ram by thumb screws passed into it from the upper surface.

The present improvements will be described with reference to a convenient form of my invention as illustrated in the accompanying drawings, in which—

Figures 1 and 2 are front and side elevations and Fig. 3 a part plan view, respectively, and Fig. 4 is a detail. Figs. 5, 6, 7 and 8 illustrate a modification for producing two small blocks, instead of one large one.

Referring to Figs. 1 to 4, a frame 1 is provided, supported on wheels or casters 2.

A mold-box 3 is mounted on hinges 4, 4.

at the ends of four equal rocking arms 5, 6. Two of these arms 5 are keyed radially at their other ends upon a bar 7 which is journaled across the frame and is rotatable on its axis to a limited extent by means of a lever 8 keyed thereon. The other two arms 6 are free to oscillate in the same way upon another bar 9 set parallel with bar 7 at the same level and at such a distance that the arms 6 are always parallel with the arms 5 and follow their motion so that the mold-box 3 is always held level upon its hinges.

The outward and inward swings of the lever 8 thus carry the mold-box without any jar or shock in an arched curve into the positions for emptying and filling and for pressing respectively (indicated by dotted lines in Fig. 2).

20 In its inner position the box 3 rests upon adjustable conical steel studs 10 fixed in the bed plate or platform 11, and corresponding sockets 12 are provided under the box so as to insure its exact position under 25 a ram-plate hereinafter described for each pressing operation.

The box 3 is provided with hinged sides 3^a and front 3^b all of which are locked by two catches 13 hinged on the sides 3^a. This 30 catch 13 is clearly shown in plan in Fig. 4. The fastening depends also upon hooks 14 mounted on the edge of the front plate so as to overlap and therefore retain the side 3^a in upright position so long as the hinged 35 front 3^b is also upright. The catch 13 is an arm carrying an inclined boss 13^a which wedges itself upon the topmost hook 14 (or it might do so direct upon the front 3^b, if preferred) when the catch 13 is swung down into a horizontal position as drawn.

40 The ram-plate 15 is mounted upon a plunger rod 16 and controlled by strong rods 32 fixed vertically upon the ram-plate and slideable in guide holes formed in long lugs 33 integral with the frame 1.

The plunger rod 16 has an upper part 16^a, in line with it but interrupted in continuity by a slide box 19 set horizontally and having central bosses 19^a with sockets 50 into which are fixed the ends of the portions 16 and 16^a respectively. The upper portion 16^a extends into a guide sleeve 21 which is a part of an upper and removable portion 22 of the frame 1. The slide-box 19 incloses a rectangular sliding block 23 having a central horizontal hole, transverse to the slide, through which is passed a strong pin 25 rotatable therein which projects and is held eccentrically in the hub 26 of a 55 gear wheel 27 rotated by a pinion 17 integral with a hand-wheel 29 bearing a handle 28.

The pin 25 is thus driven around in a circular path, at right angles to its axis, and carries with it the slide-block 23 which 60 adjusts itself within the slide box 19 and

conveys thereto a direct vertical pressure during every part of the stroke, which direct pressure is communicated to the ram-plate 15 and to the material in the box 3, thus insuring perfect evenness in the resulting block and avoiding the risk of its becoming tapered in shape through inequality of pressure.

To operate the machine, the mold box 3, being in the outer position, is filled with the 75 prepared material and roughly leveled with a float. It is next swung underneath the ram-plate 15 by manipulation of the lever 8, and the gear wheel 27 is rotated by means of the handle 28 of the wheel 29. This 80 causes the ram-plate 15 to descend to its lowest position within the box 3 and then to rise clear of it when the stroke is completed. The box is then swung back by the lever 8 to its outer position, the catches 13 are 85 thrown back, the sides 3^a and ends 3^b swung open and the pressed block removed on a pallet or special carrier. A fresh pallet is placed in the box which is then ready for a further supply of material.

90 The hand-wheel 29 may be removable and the pinion 17 may be rotated by any suitable mechanical power.

If bricks or small blocks are required several mold-boxes and ram-plates can be 95 mounted to press simultaneously at each stroke. A more convenient device for molding half blocks is shown in Figs. 5 to 8 which illustrate the mold-box and ram upon a larger scale, other parts of the machine 100 being omitted. The ram 15 is provided with a thin strip 33^a fixed transversely upon its under surface by wing nuts 34. The mold-box is slotted vertically in its front wall with a closed slot, and this is occupied by a 105 slide-plate 35 which extends completely across the mold-box, its position coinciding with that of the strip 33^a. The plate 35 is longer than the width of the box, and its projecting end is shaped to form a handle 110 as seen in Fig. 8. In operation, the strip 33^a (which may be tapered to a narrow edge) sinks into the top of the material, meeting (or nearly meeting) the plate 35, and thus two separate (or easily separable) blocks 115 are molded simultaneously. It might be possible in some cases to dispense with the strip 33^a. If desired, more than one of these slide-plates may be used in different positions in the mold-box.

120 I claim—

1. A block pressing machine having means for lifting a mold in or out of the position for pressing consisting of four equal rocking arms, each of which is hinged 125 at one end to the said box and each of which has its opposite end pivotally supported, means for pivotally mounting the arms, a bed plate having studs thereon, the said box having sockets in its bottom to re- 130

ceive the studs, and a slidable plate adapted to be inserted through a wall of the mold box and withdrawn after use.

2. A block pressing machine having means for lifting a mold in or out of the position for pressing consisting of four equal rocking arms, each of which is hinged at one end to the said box and each of which has its opposite end pivotally supported, means for pivotally mounting the arms, a bed plate having studs thereon, the said box 25 having sockets in its bottom to receive the studs, a slidable plate adapted to be inserted through a wall of the mold box and withdrawn after use, a ram coacting with the mold box, facing strips on the under surface 30 of the ram, means for imparting vertical motion and pressure to the ram, comprising upright guides and rods, a horizontal slide box having a perforated slide block, a rotatable pin in the slide block at right angles 35 to its axis, and a disk in which the pin is eccentrically fixed.

3. A block pressing machine having means for lifting a mold in or out of the position for pressing consisting of four equal

rocking arms, each of which is hinged at one end to the said box and each of which has its opposite end pivotally supported, means for pivotally mounting the arms, a bed plate having studs thereon, the said box 25 having sockets in its bottom to receive the studs, a slidable plate adapted to be inserted through a wall of the mold box and withdrawn after use, a ram coacting with the mold box, facing strips on the under surface 30 of the ram, means for imparting vertical motion and pressure to the ram, comprising upright guides and rods, a horizontal slide box having a perforated slide block, a rotatable pin in the slide block at right angles 35 to its axis, and a disk in which the pin is eccentrically fixed.

In testimony whereof I have signed my name to this specification.

FREDERICK WEBSTER KIDDIE.
